UNITED STATES PATENT OFFICE.

PETER JOHNSON LUNDEN, OF BROOKINGS, SOUTH DAKOTA.

SNOW-PLOW.

SPECIFICATION forming part of Letters Patent No. 732,646, dated June 30, 1903.

Application filed April 13, 1903. Serial No. 152,413. (No model.)

To all whom it may concern:

Be it known that I, PETER JOHNSON LUNDEN, a citizen of the United States, residing at Brookings, in the county of Brookings and 5 State of South Dakota, have invented certain new and useful Improvements in Snow-Plows; and I do declare the following to be a full, clear, and exact description of the invention, such as will enable others skilled in the art to 10 to which it appertains to make and use the same.

This invention relates to snow-plows of the character adapted to be attached to the front of a locomotive or motor-car and to be propelled forward thereby to remove the snow 15 from the trackway.

The object of the invention is to provide a plow of this character which is efficient, durable, and inexpensive, adapted alike for electric and steam railway work and designed to 20 allow the snow to be taken up and dumped at the sides of the trackway at desired intervals, and which, furthermore, may be operated by suitable mechanism actuated by the motive power of the locomotive or motor-car.

25 With these and other objects in view the invention consists of certain novel features of construction, combination, and arrangement of parts, as will be hereinafter more fully described, and particularly pointed out 30 in the appended claims.

In the accompanying drawings, Figure 1 is a perspective view of a snow-plow embodying my invention. Fig. 2 is a bottom plan view of the same. Fig. 3 is a vertical longitudinal section. Figs. 4 and 5 are vertical transverse sections on the lines 4-4 and 5-5 of Fig. 3.

In carrying my invention into practice I provide a truck-frame or supporting-framework 1 of suitable form and construction 40 and mount the same upon wheels 2 to provide a car which may be propelled by a locomotive or motor-car along the trackway to be cleaned from snow. This truck-frame is provided at its forward end with a scoop or 45 shovel 3 to take up the snow as the device is propelled along, and the rear of the same is formed with a platform longitudinally divided to provide tilting sections 4 and 5, which are hinged or pivoted at their outer edges to the 50 framework and are adapted to tilt in reverse directions to discharge the snow upon oppo-

site sides of the trackway. Rising from the framework immediately in rear of the plow or shovel is a vertical divider 6, which breaks up the snow passing from the shovel onto the 55 platform and at the same time divides it, so as to cause a like amount to be conveyed as the car moves along to the two tilting sections.

The platform-sections are actuated through 60 the medium of a longitudinal rod 7, disposed beneath the framework, which rod is connected to a pair of bell-crank levers 8, located near the front and rear ends of the car. Each of said bell-crank levers comprises a crank-arm 9, which is jointed to the rod 7, a cross-piece 10, to which said arm is connected, and a pair of arms 11, rising from the opposite ends of said cross-piece. The arms 11 are forked or bifurcated at their upper ends to 70 receive links 12, which are pivoted thereto and to other links 13, the latter-named links being in turn bifurcated at right angles to their pivotal connection with the links 12 to receive a lug or depending portion on the 75 bracket-plate 14, secured one to each of the said tilting platform-sections 4 and 5. By this construction it will be seen that when the rod 7 is moved rearwardly the crank-arm 9 will be drawn upon to elevate the arms 11 80 and to thereby leave the free sides of the platform-sections to tilt the same to an inclined position, so that the snow will discharge therefrom to opposite sides of the trackway. The connection between the link 85 13 and bracket 14 allows the sections 4 and 5 to tilt freely without strain on the bell-crank lever or pivot 12.

In practice the rod 7 may be operated by compressed air, electromechanical devices, 90 steam, or mechanical connections of any preferred kind actuated by the motor mechanism of the locomotive or motor-car used to propel the plow.

At the rear portion of the plow or scoop 3 95 is a tilting guard or fender 15, which normally lies flush with the bottom surface of the plow and is adapted to be tilted vertically against the divider to serve as a stop to prevent the snow on the platform from sliding forward 100 when the plow is brought to a quick stop or is being backed away from a snow-drift. This

guard is automatically operated when the plow is brought to a stop or backed by means of an actuating-rod 16, disposed upon the under side of the truck-frame and connected at 5 its forward end to one arm of a central pivoted lever 17, the other arm of which is jointed by a link 18 to a bracket 19 on the guard. The rear end of the rod 16 has an eye 20, by means of which it may be connected to the coupling-
10 pin of the propelling-locomotive or motor-car, so that when said car stops suddenly or backs the play between the connecting-couplings will cause the rod 16 to be drawn upon to operate the guard, thus preventing the snow
15 from shifting forwardly.

In the operation of the device the snow-plow is attached to the front end of the locomotive or motor-car and propelled forwardly, and the scoop or shovel 3 takes up the snow, which
20 by the forward motion of the car is caused to pass upon the tilting platform, the seats of which are raised at determined intervals or desired periods to effect the discharge of the snow. When the locomotive or motor-car is
25 brought to a stop or is backed on encountering a drift too heavy for the plow to go through under normal speed, the snow is prevented from shifting forward and clogging the scoop by the guard, which is actuated in the manner
30 previously described. By the use of the divider 6 the snow is prevented from accumulating in lumps and passing unequally between two platform-sections, so that both sections will receive substantially the same
35 amount of snow, thus enabling them to be operated easily and without binding.

The device is efficient in action and may be used for either street or steam railway work.

From the foregoing description, taken in
40 connection with the accompanying drawings, the construction and operation of the inven-

tion will be readily understood without requiring a more extended explanation.

Various changes in the form, proportion, and the minor details of construction may be 45 resorted to without departing from the principle or sacrificing any of the advantages of this invention.

Having thus particularly described my invention, what I claim as new, and desire to secure by Letters Patent, is—

1. In a snow-plow, the combination with a supporting-frame provided at its forward end with a shovel or scoop, of a platform composed of tilting sections, means for tilting said sections, and a divider at the forward end of the platform and between the sections, substantially as described. 55

2. In a snow-plow, the combination with a supporting-frame provided with a scoop, of a 60 platform, means for removing the snow therefrom, and a guard at the forward end of the platform operable to prevent the snow thereon from shifting forward when the plow is brought to a state of rest or backed, substantially as set forth. 65

3. In a snow-plow, the combination with a supporting-frame provided with a plow or shovel, of a platform composed of tilting sections, means for tilting said sections, a guard 70 at the forward portion of the platform, and means for elevating said guard to prevent forward shifting of the snow, substantially as described.

In testimony whereof I have hereunto set 75 my hand in presence of two subscribing witnesses.

PETER JOHNSON LUNDEN.
